UNITED STATES PATENT OFFICE.

A. ROBINSON, OF NEW YORK, N. Y.

IMPROVEMENT IN FABRICS FOR ROOFING.

Specification forming part of Letters Patent No. 36,484, dated September 16, 1863.

To all whom it may concern:

Be it known that I, A. ROBINSON, of the city, county, and State of New York, have invented a new and Improved Fabric to Serve as a Foundation to Receive Cement for Roofing Purposes; and I do hereby declare that the following is a full, clear, and exact description of the same, reference being had to the accompanying drawings, making a part of this specification, in which—

Figures 1 and 2 are face views of a portion of fabric which constitutes my invention; Fig. 3, a section of Fig. 1, taken in the line XX.

Similar letters of reference indicate corresponding parts in the several figures.

The object of this invention is to obtain a cheap and durable fabric to be applied to the roofs of buildings to receive any suitable cement which may be used as water-proof covering.

The invention is designed to supersede canvas and other fabrics which have been hitherto used for the purpose, as well as paper, which has also been used without any special preparation, but has not proved to be durable.

The invention consists in the employment or use of paper of any suitable kind, cut into strips of a proper width and twisted or folded in the form of twine or cords, said paper cords being then wove into a fabric having both a warp and a filling or weft of the same material, or having one of the aforesaid parts of twine or cords formed of hemp, cotton, or other material.

The paper I prefer to use, in consequence of answering a desirable purpose and being the most economical, is the ordinary thin "brown" or Manila paper, such as is commonly used for wrapping up light wares and articles of merchandise. This paper is cut into strips *a*, of any suitable width and length, and the strips are twisted slightly by any proper means, so as to form cords *b*. These cords *b* may form both the warp and the filling or weft of the fabric, and the warp is adjusted or fitted in a loom and the filling or weft interwoven in the warp in the same way as any ordinary or common textile fabric is produced. In Figs. 1 and 3 both the warp and filling or weft are shown formed of the paper cords. This would probably be the most desirable fabric; but a very valuable fabric for the desired purpose might be pro-

duced by having the filling or weft formed of paper cords, and the warp formed of ordinary hemp or cotton twine, *c*; or cords of other materials used in textile fabrics may be employed, (see Fig. 2;) or the warp may be of paper cords and the filling or weft formed of the twine or cords aforesaid.

An ordinary loom of the simplest kind may be employed for weaving the fabric, and a very simple twisting apparatus would answer for twisting the paper strips.

The fabric thus produced forms a very strong and durable foundation for receiving the various cements used for roofing purposes, while it is much less costly than canvas or strong muslin hitherto used. Ordinary unprepared paper is not at all durable; but it has been used to some extent on the score of economy. By my invention a fabric is obtained which will but slightly exceed in cost the simple unprepared paper and still be as durable as the cloth or canvas hitherto used for the purpose.

The fabric thus made also has a considerable thickness or body, so that where covered with the cement a thick roofing substance or material is obtained, and one which will not crack in being handled and rolled up. The interstices also of the fabric serve to hold the cement, so that it will not shell or peel off. The ordinary paper and canvas or muslin foundations hitherto used are comparatively thin, and a thick roofing material cannot be obtained without applying a very heavy coating of cement that will crack and shell off.

By my invention the cement may be applied to the foundation previous to its being applied to the roof, and the prepared roofing may be sold in any suitable quantities and then applied where desired, whereas the ordinary cement roofing requires that the paper or muslin be first secured to the roof and the cement put on afterward, as the thin material will not admit of good lap joints being formed.

I would remark that a very good paper cord may be made by folding or gathering the paper strips compactly together and then compressing them by a roller or rollers. In this case there would be no twist; but still quite a good cord would be obtained by such modification. It, however, would be substantially the same thing as the slight twist given them,

as the object is to form the paper into cords, in order that they may be woven.

I do not broadly claim the use of paper for roof-coverings; but

I claim, therefore, as new, and desire to secure by Letters Patent, as an improved article of manufacture—

A roofing fabric made of woven strips of

paper, or strips of paper and twine woven together, and cement, substantially as herein shown and described.

A. ROBINSON.
